CLAIM

The ornamental design for a game board, as shown and described.

DESCRIPTION

FIG. 1 is a top plan view of a game board showing my new design.

FIG. 2 is a side elevational view thereof taken at right angles to the view of FIG. 1 along either side.

FIG. 3 is a sectional view thereof taken along the lines 3—3 of FIG. 1.

The reverse side of the game as illustrated in FIG. 1 is plain and unornamented.

FIG. 3
